UNITED STATES PATENT OFFICE.

SARKIS MAKBOULIAN, OF HAVERHILL, MASSACHUSETTS.

DESIGN FOR A SHOVEL.

46,868.

Specification for Design.

Patented Jan. 19, 1915.

Application filed July 13, 1914. Serial No. 850,829. Term of patent 14 years.

To all whom it may concern:

Be it known that I, SARKIS MAKBOULIAN, a subject of the Sultan of Turkey, residing at Haverhill, in the county of Essex and State of Massachusetts, have invented a new, original, and ornamental Design for Shovels, of which the following is a specification, reference being had to the accompanying drawing, forming part thereof.

In the drawing Figure 1 is a front view

of a shovel showing my new design, Fig. 2 is a side view thereof. Fig. 3 is a sectional view on the line 3—3 of Fig. 1.

I claim:—

The ornamental design for a shovel, as shown.

SARKIS MAKBOULIAN.
